UNITED STATES PATENT OFFICE.

BERNHARDT HENRIKSON, OF CHICAGO, ILLINOIS.

HOSE-CLAMP TOOL.

1,347,579.

Specification of Letters Patent. Patented July 27, 1920.

Application filed September 21, 1918. Serial No. 255,183.

To all whom it may concern:

Be it known that I, BERNHARDT HENRIKSON, a citizen of the United States, residing at Chicago, in the county of Cook and State 5 of Illinois, have invented certain new and useful Improvements in Hose-Clamp Tools, of which the following is a specification.

My invention has for its object to produce a hose-clamp tool, for binding looped tie-wires about hose, pipes, or the like, which is efficient, handy, simple, inexpensive and durable, and it consists in the combinations and arrangements of parts hereinafter set forth and claimed.

15 In the drawings Figure 1 is a perspective view showing the device in use, Fig. 2 is a detail of a looped tie wire such as may most conveniently be applied by the use of the tool; and Fig. 3 is a longitudinal section 20 with parts in elevation.

To secure a coupling element *a* in the end of a garden hose *b*, by an outside tie-wire *c* or to apply a looped or "hair-pin" tie wire tightly around any object of small circumference, the ends of wire-limbs *c'* may be passed through the bend *c²*, tension being then applied to draw the limbs through the loop until the encircling strands are taut, and then the limbs may be bent sharply 30 back as shown in dotted lines; Fig. 1, cut off, and hammered down as hooks closely gripping the wire-bend *c²*. It is to facilitate such operations that the tool is employed.

A frame-member 6 carries both active elements of the tool, namely a clamp structure 7 for engaging the tie-limbs *c'* and a traveling presser-head structure 8, for engaging and moving the wire-bend *c²*. Specifically clamp structure 7 provides a handle or lever 9 operating a movable clamp jaw 10 in suitable fashion to grip the wire-limbs against a fixed-jaw portion or anvil surface 11 of the frame. The frame has bottom lugs 12 supporting pivot 13 for lever 9, and the jaw 10 has an eccentric end 14, toothed at 15, to close against fixed jaw 11 as handle 9 is moved rearwardly. The presser head proper, 16, is a part shaped for engagement with the wire-bend *c²*, its tapered, rounded 45 nose 17 having for this purpose a transverse groove 18. This head is mounted on the frame for linear movement without rotation, being arranged to have its movement guided by the frame and occasioned by pressure applied against the frame. Thus an offset 19 at the base of the head rigidly en-

gages a guide bar that slides through an opening 21 in the frame, just above the anvil-surface 11, and that acts both to guide the head and prevent its rotation. The head 60 is swiveled on the end of a screw-stem 22 that has thread engagement with the opening 23 in the top portion of the frame, and that, in rear of the frame, has an operating handle or wing-head 24. This screw 65 obviously will propel the head axially. The slide-bar preferably extends nearly to the hub of the screw-handle 24 so that the bar may not lose engagement with the frame when the stem 22 is screwed clear forward, 70 and for knock down purposes the head 16 is mounted detachably on the screw stem. Specifically, the forward end of stem 22 is smooth and grooved as at 26, to fit in a recess 27 in the head, a removable keeper-screw 28 taking into the groove to hold the 75 parts assembled.

In operation, when the hairpin wire has been looped around the hose, with its limbs projecting beyond bend *c²*, the tool, with its 80 head 16 suitably retracted, has its clamp jaws opened and is slipped over the wire limbs until the groove 18 in the pressure head engages the bend of the wire. Then one closes the clamp to grip both wire-limbs 85 and turns the screw-wings to push the pressure head forward. Of course the stronger the screw pressure the tighter clamp 7 holds since the strain on limbs *c'* tends to tighten the eccentric clamp and so with great ease— 90 holding handle 9 in one hand and working the screw stem with the other—one may draw the encircling wires perfectly taut. The shape of the pressure-head, 16, its accurate guidance by the screw 22 and bar 12, and 95 the fact that its end travels along between the limbs *c'* of the wire, all aid to insure perfect and uniform operation. When the tie is tight enough one merely rotates the tool bodily around the wire-bend *c²* as a fulcrum, 100 by pressure on lever 9, so that the wire limbs are hooked around the bend *c²* without the slightest liability to slippage. The tool is then detached by releasing the clamp and withdrawing the device, leaving the wire 105 ends free to be cut off and pounded down in any convenient way.

It will be understood that while I have herein described in some detail a specific embodiment of my invention many changes in 110 construction and details of arrangement may be made without departure from the

spirit of my invention within the scope of the appended claims.

I claim:

1. A tool of the character described comprising a head having a transverse groove to coat with the bend of a hairpin-wire, a screw-stem making rotatable but axially-fixed connection with the head and having a turn-handle, a slide rod paralleling the screw-stem and fixed to the head, a transverse frame member making threaded engagement with the screw stem and engaging the slide rod to be held thereby against rotation, and a single clamp jaw pivoted to said frame having provision for gripping both strands of a hairpin-wire and having a lever extending outwardly substantially at right angles to the stem, when in clamping position, and pivoted with its axis substantially parallel to the head-groove, whereby said lever acts as a handle by which the tool may be swung about said head as a fulcrum.
2. A tool of the character described comprising a head transversely grooved to coat with the bend of a hairpin-wire, a screw-stem making rotatable but axially-fixed connection with the head and having a turn-handle, a slide rod paralleling the screw-stem and fixed to the head, a transverse frame member making threaded engagement with the screw stem and apertured to receive the slide rod, and a single clamp jaw pivoted to said frame beyond the slide rod on an axis paralleling the head-groove and having provision for gripping both strands of a hairpin-wire including a lever extending outwardly substantially at right angles to the stem when in clamping position and acting to clamp when pulled to-

ward the turn-handle of the stem; whereby 40 said lever acts as a handle by which the tool may be bodily swung upon the head as a fulcrum.

3. In a hose banding tool, the combination of a short transverse frame having in 45 vertical alinement a threaded orifice, a smooth orifice and a stationary clamp jaw, a threaded stem extending through said threaded orifice and having at one end a turn-handle, a head swiveled on the other 50 end of said stem and having a cross-grooved nose, a guide rod fixed to said head extending through the smooth orifice of the frame and back nearly to the turn-handle, and a clamp lever coacting with said clamp-jaw 55 and adapted to clamp both limbs of a hairpin-wire.

4. In a tool of the character described, the combination of a frame having a screw-opening and a fixed clamp jaw parallel 60 with the axis of the screw opening and flanked by bearings, a clamp-lever pivoted in said bearings having an eccentric, toothed clamp-jaw arranged to tighten as the lever is moved away from the presser head, a 65 screw extending through said screw opening and having an operating handle, a presser-head swiveled on said screw and having a cross-grooved nose, and a bar carried by said presser head and guided in the 70 frame to prevent head-rotation, said clamp lever being disposed to stand at substantial right angles to the screw when in clamping position, whereby it serves as a single handle for swinging the tool about the grooved 75 nose of the head as a fulcrum.

BERNHARDT HENRIKSON.
